UNITED STATES PATENT OFFICE

2,177,509

TERMINAL STRUCTURE

Charles C. Abbott, Pittsfield, Mass., assignor to
General Electric Company, a corporation of
New York

Original application July 29, 1936, Serial No.
93,213. Divided and this application April 28,
1937, Serial No. 139,448

4 Claims. (Cl. 201—67)

This invention relates to terminal structures, more particularly to terminal structures for electric heaters, and it has for its object the provision of an improved method for sealing the terminals 5 of the heater.

Although not limited thereto, this invention has particular application to electric heaters of the incased or sheathed type wherein a resistance conductor embedded in an electrically insulating 10 material is inclosed by an outer metallic protective casing, such as described and claimed in my U. S. Patent No. 1,367,341, dated February 1, 1921; and it contemplates the provision of an improved method for securing the terminal housing 15 to the heater and also to the supply lead, in such manner as to prevent the admission to the terminal of fluids such as water, oil, gas, etc.

This application is a division of my copending application, Serial No. 93,213, filed July 29, 1936.

For a more complete understanding of this invention, reference should be had to the accompanying drawing in which Fig. 1 is a plan view of a sheathed electric heater embodying this invention; Fig. 2 is an enlarged fragmentary view 20 mainly in section illustrating a portion of the heater of Fig. 1; Fig. 3 is an enlarged fragmentary view mainly in section illustrating a terminal structure of modified form arranged in accordance with this invention; Fig. 4 is a fragmentary view mainly in section illustrating a modified form of this invention; Fig. 5 is a fragmentary view similar to Fig. 4, but illustrating the means of Fig. 4 as used to splice two heating units together; and Fig. 6 is a view illustrating a 25 heater similar to that shown in Fig. 4, but of somewhat different form.

Referring to Figs. 1 and 2 of the drawing, this invention has been shown in one form as applied to a dam gate armature heater comprising a pair 30 of sheathed heating elements 10 and 11 arranged in substantially parallel relation, as shown in Fig. 1. Each heating element 10, 11 preferably will be of the type described and claimed in my above-mentioned U. S. Patent No. 1,367,341. As shown, 35 each of the heating elements 10, 11 comprises a sinuous resistance conductor 12 (Fig. 2) arranged centrally of a metallic sheath 13 and supported in spaced relation with reference to the sheath by a highly compacted layer of heat refractory, electrically insulating material 14, such as powdered magnesium oxide. The left-hand ends of the 40 heaters 10 and 11, as viewed in Fig. 1, are connected together by means of a suitable plug 15 in which the ends of the sheathed heaters are received, and which has suitable means (not

shown) for electrically interconnecting the resistance conductors 12 of the two heaters. The two heaters 10 and 11 are rigidly secured together in spaced relation and at spaced intervals by suitable spacers 16. And, as shown, the heaters at 5 their ends opposite the connector member 15 are spaced apart somewhat farther than the rest of the heaters. To these ends is secured a plate member 17 that constitutes a cover when the heater is applied to the dam gate armature. It 10 will be understood that the heaters are inserted in suitable casings or channels (not shown) and that the cover plate is used to close the casings.

The right-hand ends of the heaters, as viewed in Figs. 1 and 2, constitute the terminal ends, and 15 arranged within and projecting from each of these ends of the sheaths is a suitable terminal member 18 connected to the resistance conductor 12, as shown in Fig. 2. A suitable fluid impervious seal is provided between the terminal and the 20 sheath comprising a layer of glass 19 adhering to the terminal and to the sheath, and an electric insulator 20 inserted in the glass, as clearly shown in Fig. 2. The specific seal between the 25 terminal and the sheath is arranged substantially in accordance with the seal described and claimed in the United States patent to R. J. Sutton No. 1,922,787, dated February 26, 1935.

The terminal structure for the heater further 30 comprises a suitable metallic tubular terminal housing 21 attached to the terminal end of the sheath and projecting therefrom in alignment with the sheath, as clearly shown in Figs. 1 and 2. As shown in Fig. 2, the terminal housing 21 has 35 a threaded connection 22 with the end of the sheath and is additionally secured to the sheath by means of a suitable brazed or soldered connection 23.

This brazed connection is made by forming an 40 annular recess 24 in the end of the housing 21 around the sheath, filling this recess with a brazing material 24a, and brazing this material to the housing and sheath to substantially integrally unite these members. The brazed joint will be 45 formed while the annular space between the housing 21 and the sheath is vented through a suitable aperture 25 provided in the terminal housing for this purpose. This permits the air within the annular space to vent itself when the sheath and housing are heated due to the brazing 50 operation. I have found this to be of material importance in securing a terminal housing to a sheathed electric heater. If this vent opening is not provided to permit the air to escape, I have 55 discovered that microscopic air holes are found

in the brazed section due to the trapped air tendency to escape through the brazing material while in a highly heated liquid state, and when the temperatures of the heater and housing are elevated due to the brazing operation. These microscopic air holes later on in the operation of the heater permit moisture to enter the terminal housing. This moisture weakens materially the electrical insulation in the terminal housing and ultimately will cause failure. After the brazing operation has been completed a suitable metallic plug 26 is forced into the aperture 25 and then the exposed end of the plug is brazed to the walls of the housing.

15 An electrical supply lead 27 enters the housing 21. This lead comprises an electrical supply conductor 28 which is covered by a yielding electrically insulating covering or layer 29 formed of any suitable material, such as rubber. The main 20 portion of the covering 29 in turn is covered by a suitable protective casing 30 formed of any suitable metallic material, such as lead.

Arranged within the chamber or housing 21 around the terminal and connector members and 25 the inner portion of the lead 27 is a suitable electrically insulating sleeve 31. This member may be formed of any suitable electrically insulating material, such as baked lava. Arranged on the outer end of the sleeve 31 are a plurality 30 of yieldable sealing members 32 yieldingly engaging the covering 29, and separated from each other by means of a plurality of metallic washers 33. The yieldable members 32 are forced inwardly by means of a loading plug 34. The arrangement of the sleeve 31, the washers 32 and 33 and the loading plug 34 is as described and claimed in my above-mentioned copending application Serial No. 93,213.

In Fig. 3, I have illustrated a terminal structure of modified form and arranged in accordance with this invention. In this case, the lead 35 enters the terminal housing 36 where it is connected with the terminal 37 of the heater in the same manner as in the first form described. In this case also, the terminal housing 36 is secured to the sheath 38 of the heater in the same manner as in the first form, but it is also directly connected with the metallic outer casing 35a of the lead so as to provide a fluid impervious joint at this point. For this purpose, the housing is directly connected with the loading plug 39 by means of a soldered joint. As shown, the outer section of the plug has such a diameter that when it is turned inwardly, as shown in Fig. 3, an annular space 40 is left between this section and the housing 36. Within this space is provided a suitable soldering material 41 which is soldered both to the housing and to the plug to provide a fluid impervious joint between these members. The outer section of the plug 39 in turn is secured to the metallic casing 35a of the lead by means of a soldered joint 42. The diameter of this outer section of the plug is larger than the lead, and is flared outwardly, as clearly shown in Fig. 3, to provide a space for the reception of the soldering material 42. When the soldered joint 42 is formed, the annular space between the lead sheath 35a and the plug is vented to the atmosphere through an opening 43. This vent opening, as before, is subsequently closed by means of a pin 44 which is soldered to the plug. The lead 35 is reinforced by a rubber sleeve 45 which is secured by taping 46, as described in my copending application, Serial No. 93,213.

In Fig. 4, there is illustrated a modified form of connection between the terminal housing and the sheath of the heater. As shown in this case, the terminal housing 47 is relatively long and has a close fit with the outer wall of the sheath 48. The housing 47 is provided with a pair of spaced annular passageways 49 about the sheath, each passageway opening to the exterior of the sheath through a duct to a passageway 50. The annular passageways 49 are filled with brazing material 51 through the passageways 50 to braze the terminal housing to the sheath. A vent hole 52 is provided between the passageways 49 to vent the annular space between the terminal housing and the sheath during the brazing operation. The hole 52 is subsequently closed by a pin 53 which is brazed over to secure it to the housing.

In Fig. 5, there are illustrated two sheathed heating elements 54 and 55 spliced together by a combined connector member and terminal housing 56. The housing 56 is brazed to each heating unit in the manner previously described in connection with Fig. 4. Thus, the terminal housing is provided with spaced annular passageways 57 surrounding each heating unit 54, 55 adjacent the end of the heater, as shown in Fig. 5. A brazing material 58 is inserted in these passageways and is brazed to the respective heater and housing while the annular space between the heater and the housing is vented through a passageway 59 which is subsequently closed by a pin 60 brazed to the housing. If it be desired, two vent openings 59 may be provided for each heater, as shown in Fig. 5.

The terminals 61 of the two heaters are secured together by a connector 62 threaded on the terminals as shown. Washers 63 formed of any suitable electrically insulating material, such as mica, are placed on the terminals between the ends of the heating unit and the connector 62. A sleeve 64 formed of a similar electrically insulating material is placed around the connector, as shown. The sheath of each unit is provided with a series of spaced circular grooves 65 to prevent fluxes used in the brazing operation from working along the sheath to the mica washers 63. Preferably, the annular space between the terminal housing and the sheath at the sections where the grooves 65 are formed will also be provided with vents 66 opening to the atmosphere during the brazing operation, and subsequently closed by pins or plugs 67 brazed to the housing.

In Fig. 6, there is illustrated a heater 68 having a terminal housing 69 secured to it by brazed joints 70 in the same manner as the terminal housings of Figs. 4 and 5 are secured to their heaters, but in this case the terminal housing is arranged at a predetermined angle to the main body of the heater. The housing in this case is provided with a reduced extension 71, and the angular relation between the housing 69 and the heater is applied by bending the housing at a point in the reduced extension beyond the brazed section 70, as shown. Bending the housing at this section causes it to grip the heater firmly and obviates the possibility of strains being set up in the brazed joints 70.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. In a terminal structure for a sheathed electric heater, the method of securing a terminal housing to the end of said heater which comprises forming said housing with a passageway to receive the sheath of said heater, forming a channel in said housing surrounding said passageway and sheath and opening to the exterior of said housing, forming an opening in said housing adjacent said channel to vent said passageway to the exterior of said housing, inserting brazing material in said channel and heating it to braze said housing to said sheath while said opening allows the escape of air from said passageway, inserting a pin into said opening to close it, and then brazing said pin to said housing.
2. In a terminal structure for a sheathed electric heater, the method of securing a terminal housing to the end of said heater which comprises forming said housing with a passageway to receive the sheath of said heater, forming a plurality of channels in said housing surrounding said passageway and sheath and opening to the exterior of said housing, forming a vent in said housing between said channels and connecting the passageway with the exterior of the housing, inserting brazing material in said channels and brazing said housing to said sheath, inserting a pin into said vent to close it and then brazing said pin to said housing.
3. In a terminal structure for a sheathed electric heater, the method of securing a terminal housing to the heater which consists in thread-

ing the terminal housing onto the end of the sheath, providing an annular recess in the inner wall of the housing about the outer wall of the sheath and opening to the exterior of said housing, providing in said housing a vent hole adjacent said annular recess and connecting the annular space between the outer wall of the sheath and the inner wall of the housing with the exterior of the housing, inserting brazing material in said annular recess and heating it to braze the housing to the sheath while said opening allows the escape of air from said annular space, and then subsequently inserting a pin in said vent hole to close it, and brazing the pin to the housing.

4. In a terminal structure for a sheathed electric heater, the method of securing a terminal housing to the heater which consists in inserting the terminal end of the heater into the housing, providing an annular channel in said housing arranged to surround said sheath and opening to the exterior of said housing, providing in said sheath a plurality of grooves between said channel and the end of the sheath, providing in said housing a vent hole on one side of said channel and opposite the section of said sheath where said grooves are provided and a second vent hole on the other side of said channel, then filling said channel with brazing material and heating it to braze the housing to the sheath while said vent holes are open to allow the escape of air from the space between said heater and housing and subsequently sealing said vent holes.

CHARLES C. ABBOTT.
